DESIGN FOR A BROOCH OR SIMILAR ARTICLE

Eugene S. Boudinot, Des Moines, Iowa

Application May 26, 1942, Serial No. 107,017

Term of patent 7 years

To all whom it may concern:

Be it known that I, Eugene S. Boudinot, a citizen of the United States and resident of Des Moines, county of Polk, State of Iowa, have invented a new, original, and ornamental Design for a Brooch or Similar Article, of which the following is a specification, reference being had to the accompanying drawing, forming a part thereof.

Fig. 1 is a front elevation of a brooch or similar article embodying my novel design.

Fig. 2 is a top plan view of the article illustrated in Fig. 1.

I claim:

The ornamental design for a brooch or similar article, substantially as shown.

EUGENE S. BOUDINOT.
